FIRE-EXTINGUISHING PUMP

Richard Zieschang, Brentford, England, assignor
to The Pyrene Company Limited, Brentford,
England, a British company

Application June 21, 1944, Serial No. 541,416
In Great Britain July 1, 1943

4 Claims. (Cl. 103—192)

1

This invention relates to that kind of double-acting pump in which a hand-operated piston reciprocates vertically in a cylinder placed within a container for liquid to be expelled and which may be used as a fire-extinguishing apparatus.

In this kind of pump the liquid is drawn into the cylinder on the up-stroke through a non-return valve at the bottom, and on the down-stroke it is necessary to ensure that an adequate quantity of liquid passes to the upper side of the piston so that above the piston the cylinder is full of liquid when the next up-stroke begins. In existing pumps this is done by making a large central passage axially through the piston and controlling it by a ball valve mounted in a perforated cage immediately above the piston. In use it is found that the amount of liquid discharged on the up-stroke differs from the amount discharged on the down-stroke, and that on changing over from the down-stroke to the up-stroke there is a distinct halt or check in the discharge of liquid. My primary object is to reduce this halt or check to a minimum and to render the discharge more nearly uniform throughout.

According to this invention I use a clack valve mounted above the piston to control one or more axial passages in the piston, and I find that the halt or check at the end of the down-stroke is materially reduced, apparently because of a cushioning effect produced by the body of liquid which then lies between the piston and the clack valve and which may be regarded as trapped between those two parts. I prefer to make the seal between the piston and the cylinder as close as possible and to make the clack valve wholly close the passages in the piston so that on the up-stroke the assembly acts as a solid piston displacing all the liquid before it. It is not feasible to expel all this liquid from the pump, because if this were done the amount driven out would be much greater than that on the down-stroke, during which some (and indeed the greater part) of the liquid that passes through the piston must enter the cylinder, only the relatively small remainder being discharged. Accordingly it is necessary to ensure that there is an escape path of predetermined dimensions for that part of the liquid which is displaced by the piston on the up-stroke but which is not discharged. This may conveniently be done by providing a predetermined clearance or tolerance between the piston rod and that part in which it is carried at the top of the pump.

On the down-stroke the piston and clack valve part company and liquid flows through the axial

2

passage or passages in the piston and clack-valve and into the cylinder above the clack valve, as well as to discharge outlet. By making the various passages of appropriate dimensions, it is possible to determine exactly what proportion of the liquid so displaced is delivered to the discharge outlet.

I find that by these apparently simple alterations I am in fact able to produce a considerable improvement in operation. The discharge on both strokes can be made more uniform, that is to say, substantially the same volume of liquid is expelled on each stroke, in addition to the reduction in the halt or check at the end of the down-stroke.

The piston is preferably mounted to slide on a hollow piston rod placed inside and concentrically with the cylinder and formed with two sets of ports controlled by the piston, the liquid that is being discharged passing through one or other of these sets of ports in accordance with the position of the piston and flowing through the hollow piston rod on its way out of the pump. The rod also forms a guide for the clack valve.

In order that the invention may be clearly understood and readily carried into effect, one pump constructed according to the invention, together with one modification, will now be described by way of example with reference to the accompanying drawings, in which:

Figure 1 is a central vertical section through the pump; and

Figures 2 and 3 show the piston assembly on the up and down stroke respectively.

The pump, which is intended for use as a fire-extinguisher, comprises a container 1 with a base flange 2 and a fixed head 3. A pump cylinder 4 is provided within the container and at its lower end is carried in a fitting 5 which contains a non-return valve 6 that controls an inlet passage 7 for the liquid. A hollow piston rod 8 works in the cylinder 4 and is moved by an operating handle 9. This rod is formed with two sets of ports, 10 and 11, which are controlled by a piston assembly composed of a piston 12 and a clack valve 13. The piston is provided with an expandable piston ring 14 to ensure that it makes a tight seal with the inner wall of the cylinder. The piston 12 can slide on the rod 8 between an end cap 15 and a shoulder 16 formed on the rod, and the clack valve 13 can slide between the piston and a shoulder 17 formed on the rod.

The piston 12 is formed with two narrow axial passages 18, both at such a radial distance from the axis that they are completely closed by the

lower surface of the clack valve 13 on the up-stroke. The clack valve 13 is formed with axial grooves 19 which constitute ports or passages between the valve 13 and the piston rod 8.

At its upper end the cylinder 4 makes a tight fit in a fitting 20, and the piston rod 8 passes through this fitting with a clearance 21 which provides the escape path on the up-stroke.

In operation the piston 12 and clack valve 13 are in contact on the up-stroke as shown in Figure 2 so that the passages 18 through the piston 12 are closed. In consequence the assembly then acts as a solid piston. Some of the liquid displaced flows downwards through the passages 19 and the ports 10 into the inside of the piston rod 8, and is positively expelled through the tube 22 as hereinafter described. The remainder is driven upwards and passes back into the interior of the container through the escape path 21. On the down-stroke the piston 12 and clack valve 13 part company, the ports 10 are closed and the ports 11 uncovered, as shown in Figure 3, and the volume of liquid that is to be positively expelled passes into the piston rod 8 through the ports 11. The remainder of the liquid displaced passes through the passages 18 in the piston 12 and 19 in the clack-valve 13 to the upper side of the clack valve in a volume sufficient to maintain the cylinder full of liquid above the clack valve. At the end of the down-stroke, there is of course a momentary delay while the piston 12 is stationary and while the cap 15 on the end of the piston rod 8 is moving upwards to come into contact with the piston, but it is found that in practice this has no noticeable effect on the discharge of liquid from the pump. While the piston 12 is overtaking the clack valve 13 some at least of the liquid trapped in the space between them shown in Figure 3 is being expelled through the ports 10 and this may be regarded as cushioning the change-over and largely eliminating the halt or check in the discharge of liquid at the end of the down-stroke that characterises existing pumps of the kind in question.

The liquid that enters the hollow piston rod 8 is not directly discharged from it to the pump nozzle. Instead I prefer to provide a fixed discharge tube 22 inside the piston rod 8 to make this open at the top, so that the liquid forced into the piston rod 8 flows upwards through it and then downwards through the tube 22. At the bottom the tube 22, which is carried in the fitting 5, communicates by a passage 23 with an upward discharge tube 24 that is placed within the container outside the whole piston-and-cylinder assembly and that passes out of the fixed head 3 to be joined to a hose 25 terminating in a nozzle 26.

In existing pumps of the kind to which this invention relates the liquid is forced out of the cylinder through an outlet passage in the head and this is controlled by a ball valve which is forced off its seat by the pressure of the liquid when pumping begins. However, internal pressure is often set up in consequence of an increase in the atmospheric temperature and leakage then takes place past this ball valve. In the preferred pump according to the present invention, the upper end of the tube 22 forms a comparatively small valve seat 27 which, when the pump is not in use, is tightly closed by a valve member 28 placed within the top of the piston rod 8 and urged downwards by a spring 29 which bears on the underside of the handle 9. The handle is held in the closed position by a bayonet joint 30, the female member of this joint being

fixed to the head 3 of the pump. On being released, the handle can be moved upwards and carries with it the piston rod 8 and the valve 28.

Since liquid is expelled through the escape path 21 on the up-stroke, a device 31, urged into contact with the fitting 20 by a spring 32, is provided for stripping liquid from the piston rod 8.

I find that the action of the pump is improved and the discharge made more uniform if I provide a closed air pocket in communication with the top of the pump cylinder. By this means the air is under slight compression when the pump is being operated, and so forms an elastic cushion which reduces the fluctuations or interruptions in the stream of the expelled liquid as the piston changes its direction of movement. This air pocket is provided by forming a lateral spigot 33 on the fitting 20, suspending from this a tube 34 having its upper end opening into a passage 35 in the spigot and mounting on the tube a closed hollow vessel 36, the tube projecting downwards through the top of the vessel and terminating in an open end close to the bottom of the vessel.

One advantage that is obtained by the use in combination of all the features described is that, in contradistinction to existing pumps of the kind in question, the whole pump mechanism can be tested as a unit before being installed in the container and secured to the fixed head.

The invention described and claimed in this application differs in important respects from the invention described and claimed in the applicant's Patent No. 2,401,785 which resulted from an application filed on the same day as the present application. In the invention of said patent, the claimed construction of the piston assembly is such that it resists but permits some flow of liquid through the piston and valve member passages differently during the two directions of movement of the piston assembly. Whereas, in the invention of this application, the claimed construction of the piston assembly is such that it prevents flow of liquid through the piston and clack-valve passages when the clack-valve is in engagement with the piston and permits a limited flow of liquid through the piston and clack-valve passages when the clack-valve is out of engagement with the piston. The present invention may also include in the above mentioned combination the provision of a relief opening near the top of the pump cylinder, and a closed hollow vessel connected to the pump cylinder near the top thereof and forming an air pocket, features which are not disclosed in said patent.

I claim:

1. In a fire extinguishing hand-operated double-acting pump, a vertically arranged pump cylinder provided at its bottom end with a fitting having therein an intake passage communicating with the bottom end of said cylinder and provided with a check-valve permitting liquid to enter but not escape from said cylinder through said passage; a hollow piston rod having openings therein near the lower end thereof; a piston assembly carried by said piston rod and reciprocatable in said cylinder and exerting pressure on the liquid therein during movement of said piston assembly in both directions; said assembly including a piston having a liquid passage therethrough and slidably supported for limited movement on said piston rod and cooperating with the openings therein, said assembly also including a clack-valve cooperating with the upper side of said piston and having a liquid passage

therethrough which is out of alignment with the passage through the piston, said check-valve being movable by liquid pressure during upward movement of the piston assembly into engagement with the top of the piston, thereby during said movement preventing flow of any liquid through the piston assembly, and said check-valve being movable by liquid pressure during downward movement of the piston assembly out of engagement with the top of the piston, thereby during said last mentioned movement permitting a limited flow of liquid through the piston assembly; the aforesaid fitting being also provided with an outlet passage communicating with the upper end of said hollow piston rod; whereby during upward movement of said piston assembly liquid is drawn into the cylinder through said check-valve and at the same time liquid in said cylinder above said piston assembly is expelled through said outlet passage, and whereby during downward movement of said piston assembly some of the liquid in the bottom of said cylinder is permitted to flow through said piston assembly into the space in said cylinder above the piston assembly and some of said liquid is expelled through said outlet passage.

2. A fire extinguishing pump according to claim 1, in which the pump cylinder is provided near its top with a relief opening.

5 3. A fire extinguishing pump according to claim 1, having a closed hollow vessel connected to the pump cylinder near the top thereof and forming an air pocket.

10 4. A fire extinguishing pump according to claim 1, in which the pump cylinder is provided near its top with a relief opening; and having a closed hollow vessel connected to the pump cylinder near the top thereof and forming an air pocket.
